Primary Examiner — Jennifer L Rempfer*Assistant Examiner* — Edward P Jones(74) *Attorney, Agent, or Firm* — ScienBiziP, P.C.(57) **CLAIM**

The ornamental design for a puppy incubator as shown and described.

DESCRIPTION

FIG. 1 is a front, right and top perspective view of a puppy incubator, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the puppy incubator in a usable state where the inner parts of the door features and incubator are shown, and form no part of the claimed design.

The broken lines shown in the drawings are included for the purpose of illustrating portions of the puppy incubator that form no part of the claimed design.

1 Claim, 9 Drawing Sheets(56)
